(54) **THRASHING MACHINE**

(76) Inventor: **Nicholas Goldsborough**

Nicholas Goldsborough, Talbot, Maryland

Sitter Patent

The Schedule referred to in these Sitter Patent and naming part of the same containing a description in the words of the said Nicholas Goldsborough, Inventor, of his Improvement in the machine for husking and shelling corn at one operation.

To all whom these presents shall come, Be it known that Nicholas Goldsborough of the County of Talbot and State of Maryland have invented a new and useful improvement in a machine for husking and shelling corn at one operation, and that the following is a full and exact description of the construction and operation of the said machine, as invented and improved by me.

The machine consists of a frame of timber, concrete and fastening afores. First the frame is constructed of timber, timber sufficiently large to receive the other machine very conveniently described, it is composed of four upright posts to wit the front and the back posts joined together by side rails and drop to the top rails being terminated into the middle points of the front posts and into the back posts near their upper ends forming the bearing of the cylinder shaft. The front posts are made considerably longer than the back posts and are riveted as well as the latter by a large nail, through the post as also by a cap spike which cap spike of the front posts is attached by means of three bolts and riveted as to admit of being removed. Near the middle of the frame are two other strong posts of the same height as the front posts joined into the inner sides of the top rails near having their ends terminated into the lower rails. The front faces of these posts are ground to receive the cylinder of the corn case to describe their inner faces being likewise furnished with ground near the top into which a steel plank is fitted which together with a board are riveted. Hand resting in the top edge of the sides of the frame receive the cylinder or cylinder head. Then the cylinder is made of solid wood turned at the ends having iron sole plates which are in diameter to be secured on the top of the side rails midway between the front and middle posts and projecting from the rails are furnished with broad plates differing in size so as to lay the cylinder the

With one end of bars, bedded in the back of the Cylinders, into heights of 3 inches, the other of which being square is driven perpendicular into the cylinder, after being bent so that it projects at a stand in parallel, and along the cylinder, with the other of these angles forward the back of each rear standing opposite the spaces in the adjoining arms. The dimensions of the Cylinder might be as follows, those which I find convenient will be 12 inches diameter by 2 feet 8^{1/2} inches long, with a wire road of 10^{1/2} and the whole 6 and 8 inches diameter.

Within the Circles which occupies about one third of the circumference of the Cylinder, immediately under it is formed of stiff wire, two iron bars, one with four angles which rest in the spaces, the other two bars, contained in the cast iron plates that are set in and secured to the strong plates, sacrificing, or giving, which after the bars ligatured with a strong screw, wire, or wire, are placed in them. Slides in between the front posts, these bars entering the front plates to the middle plates already mentioned, by which and the stone bolts that secure them to the front posts, they are held firmly in place; the bars about 18 in all, are arranged, nearly touching each other, so that one of them angles is near the Cylinder and within about one inch distance from the ends of the bars, being found that the best distance in practice, is to make the bar extend to the tip of the arms of two angles, wire and instead of being placed diagonally as with these angles, next to the Cylinder, their faces from a continuation of the plating the feeding spoon, the effect of which is to cause the grain to feed regularly.

These bars are not placed in actual contact but with a small space between them. The other sections or joined similar to these, just described, and similarly attached to the plates rest on the upper edges of the lower joints with which they are so matched and joined of them being arranged that, in the upper part, they may be substitutive in place of the bars. At the corners the upper the edges of both joints being substituted for the top edge of the joints of the Cylinder.

(The smaller plates are so delineated as to bring the bars when in them to about a point 4^{1/2} of one inch from the Cylinder, with the bars being the best distance for throwing out wheat ahead, may be caused to use the machine for that purpose, after the bars are fastened.

are to be placed diagonally without exception. During the feeding operation which in my machine is not confined, is made in the usual manner of light boards with side pieces. The under side of the light or side edge which rests in the crevices of the joints already mentioned is furnished with a strip of wood which forms a shoulder that prevents its slipping forward.

The tip of the open must be at the distance of the Cylinder below the level of its centre and the inclination should be 80°. This is intended to receive the cornet which is suspended to the front post of the Cylinder and the use of which is to prevent the grain being thrown to a distance when discharged from the machine as its characteristic and use are known to every one conversant with the subject.

Operation. The machine being set in revolution by hand or other power applied to the hand putting the ears of corn in the brush and then a open the open and immediately pass down to the first hand of the concave where from the previous rotation, positioning the parts they are actuated by the teeth of the Cylinder to cause the corn to be taken from the diagonal bars & teeth by the joint operation of which the brush is rotated and the corn passed the whole being afterwards discharged on the opposite side of the machine, after discharging the dust although it is not mentioned in the description of my machine I use a cleaning ^{constructed} apparatus consisting of light boards distributed over the cylinder instead of the ears or hand brush described being gathered like an ordinary hand cleaning brush & passed over and carried straight up through the roof of the bars or light boards enough not to allow the grain to pass out. From practice it has been found that the brush is not only required but to be fine strips and perfectly cleaned from dust and grit by which it is well prepared indeed for work and is rendered more acceptable. The machine performs all its operations with great rapidity being as fast as the other active hands are used to them. The sand upon the open is also struck clean perfectly clean which has been previously brushed off. It is desired to finish what the Cylinder has to turn and caps pieces being removed and the same being the joints will turn the concave and cylinder are taken out and the bars shifted to the upper joints which are substituted for the last and the latter placed above the

that the right-hand upper joint occupies the place of the lower, left-hand one and the reverse, the lower, left, & upper parts being retained in their places.

Then apply a board placed edge-wise on the ground under the carriage out of which a circular dogwood is cut so as to adapt it to the circumference of the carriage, the object of which is to stiffen the board and prevent any spring of which there should be some when threshing wheat, the velocity of the beater is then increased by using the circular gutter, the wheat is then thrown into the machine in the usual way, and by its operations threshed perfectly clean. The operation continues but less fully, so that it appears that this last arrangement is equally well adapted to small grain and all the varieties of grass seeds.

Now what I claim as new in the above machine and as my improvement for which I ask Letters Patent as the continuation and arrangement of its parts by the operation of which as herein set forth and described the grain is not only threshed, but also cleaned and the trash thereby rendered much more suitable food for stock.

Witnessing that the foregoing is a true specification of my said improvement I have caused set my hand at the city of Washington this 4 day of March 1834.
